CLAIM

The ornamental design for a vehicle sensor lens hood, as shown and described.

DESCRIPTION

FIG. 1 is a perspective view of a vehicle sensor lens hood; FIG. 2 is a perspective view of the vehicle sensor lens hood of FIG. 1;

FIG. 3 is a right elevational view of the vehicle sensor lens hood of FIG. 1;

FIG. 4 is a left elevational view of the vehicle sensor lens hood of FIG. 1;

FIG. 5 is a bottom view of the vehicle sensor lens hood of FIG. 1;

FIG. 6 is a top view of the vehicle sensor lens hood of FIG. 1;

FIG. 7 is a back elevational view of the vehicle sensor lens hood of FIG. 1;

FIG. 8 is a front elevational view of the vehicle sensor lens hood of FIG. 1;

FIG. 9 is a perspective view of a vehicle sensor lens hood;

FIG. 10 is a perspective view of the vehicle sensor lens hood of FIG. 9;

FIG. 11 is a right elevational view of the vehicle sensor lens hood of FIG. 9;

FIG. 12 is a left elevational view of the vehicle sensor lens hood of FIG. 9;

FIG. 13 is a bottom view of the vehicle sensor lens hood of FIG. 9;

FIG. 14 is a top view of the vehicle sensor lens hood of FIG. 9;

FIG. 15 is a back elevational view of the vehicle sensor lens hood of FIG. 9;

FIG. 16 is a front elevational view of the vehicle sensor lens hood of FIG. 9;

FIG. 17 is a perspective view of a vehicle sensor lens hood;

FIG. 18 is a perspective view of the vehicle sensor lens hood of FIG. 17;

FIG. 19 is a right elevational view of the vehicle sensor lens hood of FIG. 17;

FIG. 20 is a left elevational view of the vehicle sensor lens hood of FIG. 17;

FIG. 21 is a bottom view of the vehicle sensor lens hood of FIG. 17;

FIG. 22 is a top view of the vehicle sensor lens hood of FIG. 17;

FIG. 23 is a back elevational view of the vehicle sensor lens hood of FIG. 17; and,

FIG. 24 is a front elevational view of the vehicle sensor lens hood of FIG. 17.

(Continued)

The broken lines in FIGS. 9-24 is for illustrative purposes only and forms no part of the claimed design.
